RADIO

Morris Fink, Great Neck, N.Y., assignor to Windsor
Industries, Inc., Plainview, N.Y.

Filed Dec. 4, 1972, Ser. No. 311,476

Term of patent 14 years

Int. Cl. D14—03

U.S. Cl. D56—4 B

FIG. 1

FIG. 2

FIG. 3

FIG. 4

FIG. 5

FIG. 6

FIG. 7

FIG. 1 is a top plan view of a radio, showing one form of my new design;

FIG. 2 is a front elevational view of the form shown in FIG. 1;

FIG. 3 is a left end elevational view of the form shown in FIG. 1;

FIG. 4 is a right end elevational view of the form shown in FIG. 1;

FIG. 5 is a rear elevational view of the form shown in FIG. 1;

FIG. 6 is a bottom plan view of the form shown in FIG. 1; and

FIG. 7 is a right end elevational view of a radio, showing another form of my new design wherein a band of contrasting appearance extends entirely around the upper member indicated by the stippled area.

I claim:

The ornamental design for a radio, as shown and described.
